S. P. Johnson,
 Invalid Bedstead,
 No 70,722. Patented Nov. 12, 1867.

S. P. Johnson

United States Patent Office.

S. P. JOHNSON, OF PORTLAND, MAINE, ASSIGNOR TO HIMSELF AND CHARLES B. WHITTEMORE, OF SAME PLACE.

Letters Patent No. 70,722, dated November 12, 1867.

IMPROVEMENT IN INVALID-BEDSTEADS.

The Schedule referred to in these Letters Patent and making part of the same.

TO ALL WHOM IT MAY CONCERN:

Be it known that I, S. P. JOHNSON, of Portland, in the county of Cumberland, and State of Maine, have invented a new and useful improved Bedstead; and I hereby declare the following to be a full, clear, and exact description thereof, which will enable others to make and use my invention, reference being had to the accompanying drawings, forming part of this specification, in which—

Figure 1, plate 1, shows a detail of the inside of the frame of the bedstead, to which is attached a ratchet, and indicates the method of operating the same.

Figure 2, plate 1, is a side elevation of my invention, with the legs or supports dropped down.

Figure 3, plate 1, is a top plan of my invention.

Figure 1, plate 2, a side elevation of my invention, illustrating the method of its operation when used as a chair.

Figure 2, plate 2, a section of the frame, showing the position and form of the double lever.

Same letters show like parts in all the plates and figures.

The object of my invention is to produce a bed-frame and bedstead that can be used with any other bedstead, like the frames of ordinary slat-beds; by itself as a cot, or either in another bedstead or by itself, as a sick or easy-chair.

a shows a frame, upon which rests the jointed frame *b b'*, by the centre part *c*, which is rigidly attached to it. In the sides of the frame are the joints or hinges *d e d' e'*. The whole frame, composed of the parts *b b' c* and *a*, rests upon legs 1, 2, 3, 4, &c., which may be turned or folded up on the inner and outer sides of different parts of the frame, as indicated in fig. 1, plate 1, but when placed in position for use, are held by slotted braces 5 in the manner shown in fig. 2, plate 1, a small pin on the leg slipping, for this purpose, into the transverse slot *f*, after passing down the longitudinal slot. When these legs are folded up on the inner or outer sides of the frame, then my invention can be placed in a common bedstead, such as is used for a slat-bed. The part *b* of the frame can be tipped up so as to form a chair-back or a rest of the back and head of a person, and the part *b'* turned downward, so as to allow the feet to hang down as in a chair. These operations are illustrated in fig. 1, plate 2. At or near the centre of the frame, and on the under side thereof, is attached the double lever *g*, hung on a pivot, so as to allow it to swing easily. By this lever, when the foot *b'* of the bed is dropped, the head *b* is raised, and when the head *b* is dropped the foot *b'* is raised so as to make the bed level again. When the frame is slatted, as 6, 7, 8, &c., then two pieces, *u v*, are placed on the under side of the slats for the ends of the lever to operate against. In fig. 1, plate 1, *n* shows a ratchet hung on a pivot, *i*. This ratchet is operated by the lever *j*, which has connected with it the rod *k*, extending a little beyond the head of the bed-frame. By drawing this rod outward from the bed-frame or bottom, the lever *j* strikes the curved end of the ratchet, and raises it from the pin *m*, over which the notches on the ratchet are made to fit, as seen in the drawing. This ratchet *n* is used to hold the bed-head *b*, when raised to any desired inclination, in such position, and when the ratchet is raised from resting on the pin *m*, by means of the rod *k* and lever *j*, then the head of the bed *b* will fall to a level position, raising at the same time the part *b'* by means of the bent double lever *g*. The teeth of the ratchet *n* are so made as to permit it to slide over the pin *m* quite easily as the head of the bed is raised, but so as to hold the head, when thus raised, at any desired point. The last of these recesses formed in the ratchet is of different shape from the rest, being square or straight-sided. (See *p*, fig. 1, plate 1.) When the pin *m* is in this recess *p* of the ratchet, then the head *b* of the bed cannot be lifted either by pressing upward on the head or downward on the foot-portion *b'*, because the form of the recess *p* will not permit of the ratchet passing over the pin. The ratchet *n* must, when in this position, be first raised by the rod *k* and lever *j*, and the head *b* of the bed be then lifted till the recess *p* has passed over the pin *m*. The purpose of this is that when the whole frame or bottom is placed level, as in fig. 2, plate 1, any weight resting on the foot-portion *b'* will not accidentally depress the same, and raise the head part *b* when such position is not desired, as the ratchet *n* and pin *m* then lock the hinge *d'*. As before intimated, all the legs 1, 2, 3, &c., may be folded or turned up, and then the bottom can be used in a bedstead, or the legs may be dropped, as in figs. 2, plate 1, and 1, plate

and the frame *a* used independently of any other bedstead, as a cot-bed or bedstead of itself. In either case can be converted into an easy-chair for invalids, and the parts held at any desired inclination in the manner more described.

I do not claim the folding frame *b c b'*, for folding beds have before been made by joints in the side pieces med in the wood thereof. Neither do I claim attaching the bottom of a bed or part thereof to a series of ers pivoted to the side rails of a bedstead, so that they may, by naturally acting upon one another by power lied at the end of the bed, convert the bed into a seat, as is seen in the patent of Jacob H. Gibson, March 1866, No. 52,988. The folding of the frame in my invention is different, from its acting only by the hinges *d' e'* and the double lever *g*.

My invention may be used either with a mattress or a canvas cover attached to the bed-frame, with springs, is common.

I do not claim broadly legs with slotted braces; neither do I claim cross-legs, one of which is slotted, and other provided with a pin to fit into said slot, for the purpose of making a folding chair. (Patent of Henry Pratt, December 4, 1860, No. 30,858.) In my invention the braces have longitudinal and transverse slots, transverse slots operating as a catch for the pin on the leg; neither do I claim legs and braces to the same, exhibited in the patent of A. C. Crandal, February 9, 1864, No. 41,488. This combination of the braces, s, slots, and pins in my invention is for the purpose of folding up the leg by the side of the frame of the l-bottom, when the bottom is not to be used as a chair, but is intended to be placed in a bedstead as a bed-
tom.

What I claim as my invention, and desire to secure by Letters Patent, is—

1. The double swinging lever *g*, as and for the purposes set forth.
2. The arrangement of the folding legs 1, 2, 3, &c., having the pins on their inner sides, with the folding ices having the longitudinal and transverse slots, as and for the purposes described.
3. The arrangement and combination of the rod *k*, lever *j*, ratchet *n*; and pin *m*, as and for the purposes forth.

S. P. JOHNSON.
